(57) **CLAIM**

The ornamental design for an illuminated signaling device, as shown.

DESCRIPTION

FIG. 1 is a top isometric view of our illuminated signaling device;

FIG. 2 is a bottom isometric view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines in the drawings represent unclaimed subject matter.
